US0D1096870S

(12) **United States Design Patent** (10) Patent No.: **US D1,096,870 S**
(45) Date of Patent: ** Oct. 7, 2025

(54) **STATIC MIXER**

(71) Applicant: **Commonwealth Scientific and Industrial Research Organisation, Acton (AU)**

(72) Inventors: **Gerald Pereira, Acton (AU); David Howard, Acton (AU); Paulus Lahur, Acton (AU); Michael Breedon, Acton (AU); Philip Kilby, Acton (AU)**

(73) Assignee: **Commonwealth Scientific and Industrial Research Organisation, Acton (AU)**

(**) Term: **15 Years**

(21) Appl. No.: **29/876,011**

(22) Filed: **May 15, 2023**

(30) **Foreign Application Priority Data**

Nov. 25, 2022 (AU) 202216972

(51) **LOC (15) Cl.** **15-09**

(52) **U.S. Cl.**

USPC **D15/138; D23/209**
